LAKE TORPEDO BOAT COMPANY OF MAINE, OF BRIDGEPORT, CONNECTICUT, A
CORPORATION OF MAINE.

STORAGE-BATTERY CELL.

1,197,022.

Specification of Letters Patent. Patented Sept. 5, 1916.

Application filed June 19, 1915. Serial No. 35,022.

To all whom it may concern:

Be it known that I, EDWARD GERALD GALLAGHER, a citizen of the United States, residing at Bridgeport, in the county of Fairfield and State of Connecticut, have invented certain new and useful Improvements in Storage-Battery Cells, of which the following is a specification.

This invention relates to improvements in 10 battery-cells or tanks designed especially for use in connection with submarine torpedo boats for supplying the necessary power used in operating the boats when submerged, and other movable structures in which the employment of series of individual cells of large capacity is desirable to insure economy of space and a minimum number of connections between the cells.

The object of the invention is to produce 20 a battery-cell or tank which shall be stronger and more durable than those now in use, and one which, in the event of injury to the inner acid holding jar, the acid or electrolyte will be prevented from coming into contact with the outer metallic casing to thus insure against grounding of the battery elements, and also to prevent the destruction of the outer casing either by direct chemical combination with the acid or electrolyte, or by means of electrolysis in the 30 event of the outer casing becoming grounded through its supports or foundations.

The invention consists in constructing a battery-cell or tank of an inner jar of hard 35 rubber or other acid resisting compound, and in arranging an envelop of lead over the lower end thereof which is burned to a sleeve of lead carried by, and molded in the upper portion of the said inner jar; in the arrangement of a sleeve of non-conducting 40 material over the upper end of the inner jar, and in inclosing the jar thus constructed in a metallic casing, into which has been previously poured, in plastic state, a quantity 45 of suitable non-absorbent and electrically non-conducting waterproof substance of hardening plastic material, the outer metallic casing being of such a size relative to the inner jar, that when the latter is inserted into the metallic casing, the plastic non-conducting 50 waterproof material will be forced upwardly into the recesses between the envelop and the outer metallic casing, and also between the sleeve and the outer metallic

casing, thus thoroughly insulating the lead 55 envelop from the outer metallic casing, the said plastic material making a composite mass when it becomes hard and cold.

The invention further consists in the employment of a cover for the cell or tank, 60 and in the peculiar and novel arrangement for sealing the cover air- and gas-tight upon the cell.

The invention further consists in certain details of constructions, combinations and 65 arrangements of parts, and in the novel method of assembling the cell or tank as will be hereinafter fully described and then claimed.

These and other features germane thereto, 70 constitute the invention, as will be herein-after fully described and then claimed.

In the drawings, illustrating the invention, in the several figures of which like parts are similarly designated, Figure 1 is a 75 vertical longitudinal section of a battery-cell or tank constructed in accordance with my invention. Fig. 2 is a sectional plan view of the same drawn on the irregular line *a—a* of Fig. 1. Fig. 3 is a sectional 80 view drawn through the gasket employed for sealing the cover upon the tank and illustrating the normal transverse form of the gasket. Fig. 4 is a cross sectional view of the cell or tank, the cover and locking 85 means therefor being omitted. Fig. 5 is a horizontal section drawn on the line *b—b* of Fig. 4, the intermediate section of the tank being broken out and the sides thereof moved toward each other. 90

1 designates the inner jar of the tank preferably rectangular in horizontal section, and constructed of hard rubber compound or other insulating acid-resisting material. The walls of the jar are thickened at their 95 upper ends to form a collar 2 and to provide ledges 3 at the ends thereof which are designed for supports for the plates (not shown), of the cell or tank. Molded in the collar 2 is a band 4 of lead, the lower edges 100 of which extend below the collar, and to which are burned or soldered the upper edges of a lead envelop 5, which completely surrounds the lower portion of the jar 1. The said band 4 is formed with a plurality 105 of openings 6 through which the material of which the jar is composed is allowed to flow when the molding is made, the material

thus being made contiguous through the openings for the purpose of anchoring the lead band within the collar. At its sides, below the ledges 3, the jar is formed with shoulders 7, under which the envelop 5 is bent, as at 5', and fitted upon the upper end of the jar is a sleeve 8 of hard rubber or other suitable insulating material or compound, which sleeve is formed with inwardly extending flanges 9 designed to rest under the inwardly extending portions or shoulders 5' of the lead envelop 5.

The jar 1, and the sleeve 8, are incased in an outer metallic tank 10, constructed of a lower section 11, formed with vertical corrugations 12, and an upper section 13, which is connected to said lower section by means of a band 14, the latter being welded or otherwise securely connected to the sections 11 and 12. As shown, the band 14 is of greater width on two of its opposite sides so as to fit under the flanges 9 of the sleeve 8, and the lead envelop 5, respectively. In practice, the band 14 will be provided with grooves 15 (Fig. 1) so as to permit the asphaltum, hereinafter referred to, to flow from the lower section to the upper section of the tank when the same is being assembled, as will be explained later on.

30 The ends of the sections 13 of the tank 10 are formed with ears 16 having openings 16', providing lifting lugs for lowering and raising the tank or cell into and out of position. The extreme upper ends of the collar 2 of the jar 1 are formed with a continuous shoulder 17, providing a seat for the cover 18 of the tank, and the walls of the jar 1, and the vertical edges of the cover 18, are formed with recesses 19 and 20, respectively, to provide seats for a flexible gasket 21, preferably rubber, whereby the cover is securely sealed to the jar or tank. The gasket, substantially oval in cross section, (as shown in Fig. 3), is held in position, and 35 also forced into the recesses 19 and 20, by a band 22, preferably rectangular in cross section, and of suitable non-conducting material or compound, and having wedge-shape blocks 23 formed thereon, which are engaged by dogs 24 carried at the outer ends of horizontally disposed members 25 journaled at their inner ends upon screws 26, threaded into lugs 27 secured to the sides of the upper member 13 of the tank 10. The 40 outer ends of the members 25 are fitted in openings 28 formed in the upper ends of the dogs 24. When the tank is assembled and the plates are inserted therein, and the electrolyte supplied thereto, the cover is then 45 placed in position, the members 25 and the dogs 24 carried thereby having previously been swung around upon their journals 26, as shown in dotted lines in Fig. 2, then when the cover has been placed in position, the 50 horizontal members are swung around so

that the dogs will engage and ride upon the wedge-shape blocks 23 to their farthest position, thus forcing the band 22 downwardly to cause the gasket 21 to be flattened out and forced into the recesses 19 and 20, thus sealing the cover upon the tank. When the dogs 24 have been thrown around to their extreme positions, the screws 26 are tightened up to thus prevent the horizontal members 25 and the dogs 24 from slipping, 55 thus holding the cover in position.

29 designates a cradle preferably of hard wood, which surrounds the lower edges of the envelop 5 of the jar 1, the cradle being designed for centering the lower end of the jar when the tank is assembled, it being understood that the cradle will be of a size to fit the outer tank 10 rather snugly.

30 designates a filling of asphaltum cement or other insulating acid-resisting compound interposed in the spaces between the outer tank 10, the lead envelop 5, and the sleeve 8, and also in the space formed between the sleeve 8 and the collar 2, as well as the space around the lower end of the band 4.

The assembling of the tank is as follows:—The inner jar 1 with the insulated lead sleeve or band 4 is first molded and the envelop 5 is then drawn over the jar 1, the upper edges of the envelop being then burned or otherwise connected to the lower edges of the band 4 at the point 40, indicated in Figs. 1 and 3. The sleeve 8 is then drawn over the lower portion of the jar until the inwardly extending flanges 9 are brought up into close contact with the shoulders 5' of the envelop 5. The cradle 29 is then fitted over and cemented to the bottom and to the lower edges of the envelop 5, after which a quantity of hot asphaltum cement or other insulating acid-resisting hardening material is poured into the tank 10, so that when the jar 1, with its previously described parts is lowered 55 into the tank 10, the asphaltum will be forced upwardly and permitted to flow through, and to completely fill all of the spaces between the jar and the tank. When cooled, the asphaltum forms a composite mass, which serves the purpose, not only of locking the several sections of the cell together, but also that of insulating the lead lining of the jar 1, from the outer 60 metallic tank 10, in the event of the inner rubber jar becoming broken or damaged so as to allow the electrolyte to penetrate to the lead lining. The lead lining will then have the potential of the elements contained within the jar, but this potential is prevented from penetrating to the outer metallic casing by means of the insulation provided by the insulating compound 30 interposed between the lead lining and the metallic tank, and between the sleeve and the 65

said tank. In no case, however, will it be possible for the outer metallic casing to obtain a potential from the contents of the inner jar except through the possibility of the upper surface of the cover and the upper edges of the jar becoming moist with electrolyte through leakage around the joints of the cover or through failure to perfectly seal the openings through the battery terminals (not shown) leading through the cover. In the event of any possible leakage whereby the electrolyte may reach the upper metallic casing through creepage over the upper surface of the cover and the upper edges of the inner jar, thus establishing a high resistance connection between the outer metallic casing and the elements of the cell. The potential thus caused would be very slight, and owing to the very high resistance interposed, such potential may be considered negligible. When the plates are inserted within the tank and the jar 1 is supplied with the electrolyte, the top 18 is then secured in position as previously described.

I have not thought it necessary to show the plates in the cell, nor the connections through the cover 18, as this will be well understood by any one skilled in the art to which the invention relates.

While I have shown and described the inner jar 1 as having a band 4 cast therein, and an envelop 5 of lead surrounding the lower end of the jar, I desire it understood that the envelop 5 may be made to inclose the entire-body of the jar 1 and the band 4, thus dispensed with, and I, therefore, do not wish to confine my invention to the arrangement of a band 4 being cast or molded into the upper end of the jar, nor to the specific arrangement of molding the jar with the collar 2. However, the construction shown and described is preferable over any previous constructions heretofore employed.

While I have shown and described the band 22 as constructed of non-conducting material, I desire it further understood that I do not limit myself to the employment of a band of such material as it is evident the band may be made of any metal not affected by electrolyte, as the band may be constructed of a core of any desirable metal and covered with preferably antimony lead. In either case, it will be understood that a sufficient number of dogs 24 will be employed for forcing the band 22 tightly against the gasket 21 without deforming the said band, consequently to hold the cover tightly against its seat with uniform pressure.

Of course, it will be understood, that when the band 22 of metal is employed, the dogs 24 will necessarily be constructed of some non-conducting material. However, in instances where the said band 22 is con-

structed of non-conducting material, it will be understood that the dogs 24 may be of any suitable metal.

I have found, from actual experience that my composite cell has been more durable and lasting than any others heretofore produced and positively provides against the contact of the electrolyte of a cell with the outer metallic casing in the event of the inner jar being cracked or otherwise injured.

I do not claim the broad idea of employing a plastic hardening material in a cell, but

What I do claim is:—

1. A battery-cell or tank, comprising an inner jar of suitable insulating acid-resisting material, an envelop of lead surrounding said inner jar, the upper edges of said envelop terminating below the upper edges of said jar, an outer metallic casing inclosing said jar and said envelop, and a filling of insulating hardening plastic material interposed between said jar, said lead envelop, and said casing, whereby to hermetically seal the said envelop and protect it from grounding with the metallic casing in the event of the tank being immersed or through creepage of the electrolyte of the cell.

2. A battery-cell or tank, comprising an inner jar of insulating acid-resisting material, a lead envelop inclosing said jar and terminating below the upper edge thereof, said envelop being embedded at its upper end in said inner jar, an outer metallic casing inclosing said jar and said envelop, a filling of insulating hardening plastic material interposed between said lead envelop and said metallic casing, a cover for said inner jar, and means for locking said cover in position on said inner jar.

3. A battery-cell or tank, comprising an inner jar of insulating acid-resisting material having a band molded in the upper end thereof, an envelop incasing the lower end of said jar and connected to said band, an outer metallic casing inclosing the same, and a filling of insulating acid-resisting, hardening plastic material intermediate between said jar and said metallic casing.

4. A battery-cell or tank, comprising an inner jar of suitable insulating acid-resisting material having a band of lead molded in the upper end thereof, an envelop of lead incasing the lower end of said jar and burned or otherwise connected to the lower edges of said band to provide an integral construction, a sleeve of insulating acid-resisting material surrounding the upper end of the inner jar, and a filling of acid-resisting hardening plastic material intermediate said jar and said metallic casing.

5. A battery-cell or tank, comprising an inner jar of insulating acid-resisting material having a band of lead molded in the upper end thereof, the lower end of said band

- being exposed, an envelop of lead incasing the lower end of said jar, the upper edges of said envelop being burned or otherwise connected to the lower edges of said band, an outer metallic casing inclosing the same, and a filling of hardening plastic material intermediate said jar and said metallic casing.
6. A battery-cell or tank, comprising an inner jar of insulating acid-resisting material having a band of lead molded in the upper end thereof, the lower edges of said band being exposed, an envelop of lead incasing the lower end of said jar, the upper edges of said envelop being integrally connected to the lower edges of said band, a sleeve of insulating acid-resisting material surrounding the upper end of the jar thus constructed, a metallic casing inclosing the same, and a filling of hardening plastic material intermediate the spaces formed between the said inner jar, the said sleeve, and the said metallic casing.
7. A battery-cell or tank, comprising an inner jar of insulating acid-resisting material having a band of lead molded in the upper end thereof, the lower edges of said band being exposed, an envelop of lead incasing the lower end of said jar, the upper edges of said envelop being integrally connected to the lower edges of said band, a sleeve of insulating acid-resisting material surrounding the upper end of the jar thus constructed, a metallic casing inclosing the same, a filling of hardening plastic material intermediate the spaces formed between the said inner jar, the said sleeve, and the said metallic casing, a cover for said inner jar, and means for securing the cover gas-tight to said jar.
8. A battery-cell or tank, comprising an inner jar of insulating acid-resisting material having its upper end formed with a collar providing interior plate supporting ledges and external shoulders at its ends, a band of lead embedded in said collar, said band being exposed at its lower edges, an envelop of lead incasing the body of said jar having its upper edges burned or otherwise formed integral with the lower edges of said band, a sleeve of non-conducting material surrounding the upper end of the jar thus constructed, said sleeve having inwardly extending flanges engaging the portions of said envelop extended under the said flanges of the jar, a metallic casing inclosing said inner jar and said sleeve, and a filling of hardening plastic material intermediate said jar, and said sleeve, and said metallic casing.
9. A battery-cell or tank, comprising an inner jar constructed of insulating acid resisting material having a lead band molded in the upper end thereof, a lead envelop incasing the lower end of said jar having its upper end integrally connected with the lower edges of the said band, a metallic casing inclosing the jar thus constructed, a cover adapted for closing the upper end of said jar, said jar and said cover having recesses formed therein, a gasket of flexible acid-resisting material adapted to be forced into said recesses, a band fitted upon said gasket, and means carried by said metallic casing for forcing said band into engagement with said gasket whereby to force the latter into said recesses, for the purposes specified.
10. A battery-cell or tank, comprising an inner jar of suitable insulating acid-resisting material, a metallic casing inclosing said jar, a cover for said cell, a flexible gasket adapted for sealing said cover upon the cell, a band co-acting with said gasket, and means carried by said metallic casing for forcing said band down upon said gasket, whereby to seal the cover upon the cell.

In testimony whereof I have hereunto set my hand this 17th day of June, A. D. 1915.

EDWARD GERALD GALLAGHER.
